(57) **CLAIM**

The ornamental design for a bottle, as shown and described.

DESCRIPTION

1.Bottle

Fig. 1.1 is an exploded perspective view of a bottle showing my new design.

Fig. 1.2 is a side view thereof;

Fig. 1.3 is a front view thereof;

Fig. 1.4 is an enlarged perspective view thereof;

Fig. 1.5 is a bottom view thereof;

The broken lines in the Figures show portions of the bottle which form no part of the claimed design.
